(57) **CLAIM**

The ornamental design for a sample collection bottle, as shown and described.

DESCRIPTION

FIG. 1 is a front plan view of a first embodiment of a sample collection bottle;

FIG. 2 is a top plan view of the first embodiment;

FIG. 3 is a bottom plan view of the first embodiment;

FIG. 4 is a front plan view of a second embodiment of a sample collection bottle;

FIG. 5 is a top plan view of the second embodiment;

FIG. 6 is a bottom plan view of the second embodiment;

FIG. 7 is a front plan view of a third embodiment of a sample collection bottle;

FIG. 8 is a top plan view of the third embodiment;

FIG. 9 is a bottom plan view of the third embodiment;

FIG. 10 is a front plan view of a fourth embodiment of a sample collection bottle;

FIG. 11 is a top plan view of the fourth embodiment; and, FIG. 12 is a bottom plan view of the fourth embodiment.

The back plan view, left plan view and right plan view of the first embodiment are the same as the front plan view of the first embodiment, and are thus omitted;

The back plan view, left plan view and right plan view of the second embodiment are the same as the front plan view of the second embodiment, and are thus omitted;

The back plan view, left plan view and right plan view of the third embodiment are the same as the front plan view of the third embodiment, and are thus omitted;

(Continued)

The back plan view, left plan view and right plan view of the fourth embodiment are the same as the front plan view of the fourth embodiment, and are thus omitted.
